UNITED STATES PATENT OFFICE

1,998,257

GAS BURNER ATTACHMENT

Mary E. Smith, Rosedale, Kans.

Application April 23, 1934, Serial No. 721,934

1 Claim. (Cl. 158—113)

This invention relates to gas burner attachments that may be associated with natural gas burning equipment in cook stoves, heating stoves, furnaces, or any other combustion chambers where it is desirable to create an exceptionally true blue flame that will not smoke the bottoms of cooking utensils, the inner walls of combustion chambers, or any part of the heating equipment wherein such attachment is used.

10 A further object of the instant invention is to provide a new article of manufacture in the form of a deflector plate for gas burners that will act upon the jets of flame adjacent the points of combustion so that their normal paths of travel 15 will be altered and thereby made longer before the article being heated is reached.

An even further object of this invention is to provide a deflector for gas burners that has a specific relation with the apertures of a gas burner, such relation being that the major portion 20 of the jets of flame projecting from said burner are deflected while the remaining portion thereof is allowed to travel in its normal manner.

It has been proven through extended use of 25 deflectors embodying this invention that a clean flame free of hydrocarbon particles is produced and that after many hours of actual heating, utensils will not have thereon a collection or deposit of carbon black or soot which normally is 30 the case with natural gas burners not having my deflector forming a part thereof.

It has been found further, that embodiments 35 of this invention will take the form of various types of deflectors and by way of example, two of said forms are set forth in the accompanying drawing, wherein:

Figure 1 is a vertical cross section through a gas burner having a deflector attached in accordance with this invention.

40 Fig. 2 is a top plan view of the same.

Fig. 3 is an enlarged fragmentary, detailed, sectional view showing the manner of removably attaching one form of the deflector.

Fig. 4 is an inverted plan view of the deflector 45 per se.

Fig. 5 is a vertical section through another type of burner and deflector illustrative of a modified form of the invention.

Fig. 6 is a vertical, cross section through a gas 50 burner, showing a deflector, embodying this invention, associated therewith and attached thereto in a manner unlike that employed in such forms as shown in Figs. 1 and 2, and,

Fig. 7 is a top plan view of the attachment 55 shown in Fig. 6.

It is desirable to form the deflector of sheet metal and to provide integral means of attachment to the burner, and it is this preferred type of deflector that is shown in Figs. 1, 2 and 4, however, in most instances burner 10 is of the type illustrated and has a connecting pipe 12 which joins burner 10 with the conventional mixing chamber not here shown.

Burner 10 is provided with a plurality of apertures 14 formed through the upper wall 10 thereof and a number of these apertures 14 are arranged in an annular path around the central opening 16 of this type of burner. All of apertures 14 are disposed to project jets of flame in an upward direction and when the novel deflector is in position, it acts upon the major portion of these jets to deflect the same out of their path of travel while the remaining ones are allowed to continue in a normal manner.

The deflector proper is formed of sheet metal 20 and made into a frusto-conical body 18 and when applied, the edge 20 defining the smallest annular diameter is located adjacent the center of the burner. As a matter of fact, this edge intersects the axis of all of the apertures 14 25 in the aforesaid annular path and, in one form of the device, is held there by a series of tongues 22 integral with body 18. These tongues 22 are bendable and grip the inner annular face of burner 10 which forms the opening 16. In this 30 manner deflector 18 may be adjusted toward or from the face of burner 10 which has apertures 14 formed therein.

Another form of attaching means for deflector 18 is shown in Figs. 6 and 7. In these illustrations, the means comprises a number of pins 35 24 which are passed into some of the apertures 14 and allowed to rest against the annular edge 20 of deflector 18. In this form the lowermost edge is directly against the face of burner 10.

While many other forms of the deflector might be employed to produce desirable results, but one other type is here shown. Fig. 5 illustrates 40 the oven-type burner 40 having apertures 42 in the lowermost wall, from which is projected the gas at the point of combustion. Deflector 44 is V-shaped in cross section and is associated with burner 40 as shown. There is a series of spaced apart openings 46 formed along the line of meeting between the two sides of deflector 44 and it is through these openings 46 that some portion of the jets of flame will pass. The other and major part of the jets of flame will be deflected 45 and turned back upon themselves when they strike the angular surfaces of deflector 44.

When employing deflectors embodying this invention, the mixing chamber which usually governs the amount of air admixed with the natural gas is opened wide to allow as much air to enter as possible. It has been found that in so doing, after affixing this novel deflector, a true blue flame is produced which will not create soot or dirt and which is exceptionally hot. The amount of gas burned seems to be reduced for a given length of time and the saving effected, together with the desirable results, has proven to be exceptionally valuable.

Having thus described the invention, what is claimed as new and desired to be secured by Letters Patent is:

An attachment for gas burners having a series of apertures formed therethrough to permit the escape of gas at the points of combustion and including a series of apertures arranged in an annular path concentric with the axis of the burner, comprising a frusto-conical deflector plate positioned upon the burner to change the direction of travel of most of the jets of flame; and means for removably maintaining said deflector in place, the annular edge defining the smallest diameter of said deflector plate being immediately adjacent to and intersecting the axes of all the apertures in said annular path.
